PLATE OR SIMILAR ARTICLE

George Rudd, Bedford, Ohio, assignor to The
Walker China Company, Bedford, Ohio

Application June 21, 1951, Serial No. 15,620

Term of patent 14 years

(Cl. D44—15)

To all whom it may concern:

Be it known that I, George Rudd, a citizen of the United States of America, residing in Bedford, county of Cuyahoga, and State of Ohio, have invented a new, original, and ornamental Design for a Plate or Similar Article, of which the following is a specification, reference being had to the accompanying drawing, forming part thereof, wherein the figure is a top plan view of a plate or similar article, showing my new design.

The dominant feature of my design resides in the ornamentation around the periphery of the plate as shown.

I claim:

The ornamental design for a plate or similar article, substantially as shown and described.

GEORGE RUDD.
